(57) **CLAIM**

The ornamental design for a furry toy animal shell, as shown and described.

DESCRIPTION

FIG. 1 is a front perspective view of a furry toy animal shell, showing my new design therefor;

FIG. 2 is a side view therefor, showing the left side, the right side being a mirror image thereof;

FIG. 3 is a top plan view therefor;

FIG. 4 is a bottom plan view therefor;

FIG. 5 is a frontal view therefor; and,

FIG. 6 is a rear view therefor.

It should be understood that the entire body of the shell, the frontal edges of the ears, and the back of the ears are furry, but in the Figures, they are shown furry only around the edges of the body and the ears, for clarity, and that the frontal inner part of the ears and the underside of the tail are shaded to show their fabric nature.
